UNITED STATES PATENT OFFICE.

FRANCIS H. RICHARDS, OF HARTFORD, CONNECTICUT, ASSIGNOR, BY MESNE ASSIGNMENTS, TO AMERICAN TYPOGRAPHIC CORPORATION, A CORPORATION OF ARIZONA TERRITORY.

TYPOGRAPHIC FORM.

976,919.

Specification of Letters Patent. Patented Nov. 29, 1910.

Application filed July 25, 1901, Serial No. 69,621. Renewed December 2, 1908. Serial No. 465,693.

To all whom it may concern:

Be it known that I, FRANCIS H. RICHARDS, a citizen of the United States, residing at Hartford, in the county of Hartford and State of Connecticut, have invented certain new and useful Improvements in Typographic Forms, of which the following is a specification.

This invention relates to forms for use in printing, and to means for assembling lines of types, or typebars, employed in typographic composition, and which are arranged in columns or articles of a required length, enabling the assembled bars to be quickly and without practical difficulty fastened together; providing thus a compact and unitary printing-frame which may in the operation of printing be handled with the same facility as electrotype-blocks, or similar matter not set up in loose condition.

The present invention has for an object to provide a typographic form embodying a number of typebars all connected as a unit by means of a proper base-plate or carrier with which the several bars are interlocked, and the invention is further directed to the provision of a large form embodying one or more such carriers each provided with its complement of typebars.

30. In the drawings attached to the present specification, Figure 1 is a perspective view of an integral line of types whose body portion is so formed as to enable the line of types to be interlocked with a proper carrier.

35. Fig. 2 is a transverse sectional view upon a somewhat enlarged scale of such a line of types as is indicated in Fig. 1. Fig. 3 is a perspective view drawn to the same scale as Fig. 1, showing a carrier with which a line

40. of types may be interlocked. Fig. 4 is a similar view showing a typographic form embodying a number of lines of types assembled and interlocked with a carrier. Fig. 5 is a perspective view drawn to a somewhat

45. smaller scale than the preceding figure illustrating a galley or composition plate with which there has been engaged a number of unitary or small typographic forms of the general construction set forth in Fig. 4.

50. Fig. 6 is a perspective view of the end portion of a locking piece or key for securing one of the small forms to the galley or com-

position plate. Fig. 7 is a perspective view of a modified construction of a constituent part or small form. Fig. 8 is a perspective view of the carrier or base-plate indicated in Fig. 7; and Fig. 9 is a similar view of one of the integral lines of types set forth in Fig. 7.

Similar characters of reference designate corresponding parts in all figures.

In carrying my present improvements into practice and in manufacturing a typographic form, the lines of types which are assembled and connected one with the other to constitute a unitary structure may be of the species illustrated in the present drawings in which the typebar itself is an integral structure embodying a member whose integral upper edge is provided with integrally connected types or characters, although the present invention is in no wise limited in its application to the employment of such a particular kind of typebar, as in general the same is applicable to the assembling and connecting of a number of lines of type, each of which lines is provided with a body or carrier portion whether the same is in integral connection with the line of types or not.

Each typebar, designated in a general way herein in Figs. 1, 2, 4, and 5 by B, is suitably formed to engage and be interlocked with a correspondingly formed portion of a base-plate having a desired length, such, for instance, as the length of the article or column to be set up, more or less. As shown in the figures referred to, each typebar is notched in its lower edge with an under-cut slot b, while the base-plate, designated by C, is provided with a correspondingly formed guide c on its upper face. Evidently, the several bars and the base-plate when so constructed may be engaged one with the other by sliding the bars along the plate with their notches in engagement with the guide portion on the latter.

In the practical use of this typographic form, embodying the connected base-plate C and assembled typebars B interlocked therewith, the entire structure will ordinarily be made of the same metal so that the whole frame may be worked over into new plates or new bars by melting or other suitable process of reconversion without ne-

cessitating the separation of the bars from the plate.

Instead of notching the bars, as indicated in Fig. 1, and forming the base-plate with a corresponding projection, the construction may be reversed, as it were, and as indicated in the relation of the parts in Figs. 7, 8, and 9. In these latter figures each typebar B' is provided with a tenon-like projection b'' adapted to fit into the corresponding longitudinal groove b''' formed in the base-plate C'.

When the desired number of bars have been assembled and engaged with their base-plate they may be caused to be snugly held in place by peening or otherwise riveting over the metal of the bars and plates adjacent to their engaging edges to prevent the dislodgment of the former, as indicated in a general way by stippling 2 in some of the figures.

A further improvement relates to the manner of assembling these primary or small forms on a galley or main plate or frame, on which the page or sheet of typographic composition comprising one or more of the primary forms is made up and constituting what may be called, a large form. For this purpose a galley-plate B'' is shown provided on its surface with a number of grooves 12, preferably undercut and with each of which grooves there is adapted to engage a proper locking-piece or key 10 which may be slid lengthwise into place and engaged with a similarly formed groove 11, here shown as extending lengthwise of each base-plate or typebar-carrier C or C'. In some instances, and especially in cases where the column is of considerable width, necessitating a base-plate of considerable width, it may be desirable to form more than one of such grooves 11 in the bottom of a base-plate, and for the correct relation of a number of small forms to the grooves in the galley-plate the latter is provided with a plurality of such grooves disposed at intervals for receiving the locking pieces or keys. The interval between adjacent grooves may be uniform, or it may vary, only such being employed in any particular case as the width and character of the component small forms or printing-frames may require. By this means I provide for the employment of printing-frames of various width assembled and all held in place on the same galley-plate.

Having described my invention, I claim—

1. A typographic form embodying, in combination a main base plate and a plurality of column wide form base plates or carriers slidingly locked in place thereon by interlocking grooves and projections respectively and each constituting one member of a form, and a plurality of type bars constituting another member of said form, one of said members having an undercut groove,

while the other member has a corresponding projection or guide fitting into the groove.

2. A galley or main plate for making a large form, said plate being adapted to have interlocked with it a plurality of small forms, each of which comprises a plurality of type bars interlocked with a base plate whose width is substantially equal to the length of the typebars.

3. A galley or main plate for making a large form, said main plate being provided with a number of grooves and locking pieces or keys for connecting a plurality of small forms to it, each small form comprising a plurality of typebars interlocked with a base plate whose width is substantially equal to the length of the typebars.

4. A galley or main plate provided with a number of undercut grooves and locking pieces or keys for connecting a plurality of small forms to it, each small form comprising a plurality of typebars interlocked with a base-plate whose width is substantially equal to the length of the typebars.

5. In combination with a galley or main plate adapted to support a number of small forms, locking-pieces for connecting the small forms to the main or galley-plate, each form and the galley or main plate having alining grooves in which the locking-pieces are adapted to fit and each small form comprising a plurality of typebars interlocked with a base plate whose width is substantially equal to the length of the typebars.

6. The combination with a galley or main plate adapted to support a number of small forms, of locking-pieces for connecting the small forms to the main or galley-plate, each form and the galley or main plate having alining undercut grooves in which the locking-pieces are adapted to fit and each small form comprising a plurality of typebars interlocked with a base plate whose width is substantially equal to the length of the typebars.

7. A galley or main plate for making a large form, in combination with a plurality of small forms interlocked with it and each comprising a column wide base plate interlocked with said main plate and a plurality of typebars interlocked with the base plate and each approximating in length the width of the column.

8. The combination with a galley or main plate for a large form having locking means, of a plurality of small forms and each comprising a plurality of typebars and a base plate equal in width to the length of a typebar and interlocked with the typebars and with the galley or main plate.

9. A galley or main plate provided with a number of undercut grooves, a plurality of small forms each comprising a base plate having undercut grooves and a plurality of typebars interlocked with said base plate,

and locking pieces or keys in said undercut grooves for locking the small forms to the main plate.

10. In a large form, the combination with a galley or main plate provided with a number of undercut grooves, of a number of small form base plates each having an undercut groove, keys engaging the grooves in

the main plate and in the small plates and locking these together, and a plurality of 16 typebars carried by and interlocked with each small form plate.
